Filed June 3, 1965, Ser. No. 85,561

Term of patent 3½ years

(Cl. D52—2)

FIG. 1

FIG. 2

FIG. 4

FIG. 1 is a front elevation of a counter-mounted dispenser for condiments and the like embodying my new design, the dash lines indicating a counter top to which the same may be mounted, being shown for illustrative purposes only.

FIG. 2 is a right side elevation thereof.

FIG. 3 is a top view thereof with the broken line portion omitted.

FIG. 4 is a bottom view thereof with the broken line portion omitted.

The undisclosed side of the dispenser is substantially the same in appearance as the side shown, and the rear is plain.

I claim:

The ornamental design for a counter-mounted dispenser for condiments and the like, substantially as shown and described.
